GASEOUS ELECTRIC DISCHARGE DEVICE

Martin Reger, Berlin-Charlottenburg, Germany,
assignor to General Electric Company, a corporation of New York

Application August 31, 1938, Serial No. 227,831
In Germany September 18, 1937

3 Claims. (Cl. 176—122)

The present invention relates to gaseous electric discharge devices generally and more particularly the invention relates to such devices of the high vapor pressure type having a starting gas and a quantity of mercury therein which is wholly vaporized during the operation of the device.

Such devices require a series resistance to stabilize the discharge therein and choke coils and condensers have been preferred for this purpose since these types of resistances consume very little electric energy, if any. Such wattless resistances are expensive and, because of their size, must be mounted separate from the lamp device.

It is desirable to incorporate the series resistance in the structure of a lighting device to constitute a self contained unit which can be connected into the ordinary light socket without the need for any external auxiliary equipment. For this purpose a discharge lamp has been mounted together with a series connected ohmic resistance, in the form of an incandescent filament, in a sealed bulb so that the electrical energy dissipated in the series resistance is converted thereby into light and heat to improve the overall efficiency of the electric lamp. To obtain the maximum light output from the filament it must be made relatively small and, indeed, of such dimensions that, during the operation of the lamp device, it dissipates about 25 to 30% of the supply voltage. I have observed that a resistance of such size is satisfactory for ballasting the discharge lamp only when the line voltage is constant since, with a fluctuating line voltage, either the filament is overloaded and is short lived or the electrodes of the device are not maintained at a discharge supporting temperature and the discharge lamp is extinguished due to changes in current in the lamp device. For example, an increase of 5% in the line voltage, when the filament is of such size that it dissipates about 25% of the line voltage, causes a voltage increase of at least 20% across the filament.

The object of the present invention is to provide a lighting device of the above type which is highly efficient and in which the above disadvantages are avoided. Still further objects and advantages attaching to the device and to its use and operation will be apparent to those skilled in the art from the following particular description.

The invention attains its objects by connecting in series with the discharge lamp in a lighting device of the above type a resistor consisting of iron wire and by dissipating less than 20% of the line voltage in said resistor. The iron wire is mounted in the space between the bulb and the lamp and this space is filled with helium or hydrogen. The iron wire does not emit light during the operation of the lamp.

When the series resistance is a filament of the

type which is heated to incandescence during the operation and is mounted in a bulb containing a mixture of argon and nitrogen about 30 to 50% of the line voltage must be dissipated in the resistance to assure successful operation of the lamp on a fluctuating line voltage. The series resistance in a lamp embodying the present invention, however, need dissipate only 20% or less of the line voltage because the iron wire in an atmosphere of hydrogen or helium has a very steeply rising volt-ampere characteristic and is, therefore, eminently satisfactory for preventing harmful current changes when the line voltage fluctuates.

When 80% of the electric energy consumed by the electric lamp is converted into light by the arc discharge the gain in efficiency of the discharge device more than compensates for the loss of the light emitted by the series incandescent filament of prior devices as will be apparent from the following example:

When the discharge device and the incandescent filament are so dimensioned that the lamp device operates on 220 volts and the filament dissipates 110 volts the efficiency of the filament is 17 lumens per watt and the efficiency of the discharge device is 37 lumens per watt. The overall efficiency of the lamp device is thus 27 lumens per watt. When the operating voltage of the discharge device is 180 volts, in accordance with the present invention, the efficiency of the lamp device is 0.8×37 lumens per watt or 30 lumens per watt, a gain of about 10% in efficiency.

The operating voltage of the discharge is determined by the distance between the electrodes and the vapor pressure. In order to start and operate the lamp device on alternating current it is desirable that the reignition voltage on each half cycle does not exceed the operating voltage by more than 20%. This can be assured by providing auxiliary, starting electrodes in the discharge device.

During the starting period of the lamp it is desirable to connect a second resistor in series with the iron wire in order to control the starting current. When the discharge device is at operating equilibrium the starting resistance is short-circuited by a third resistor having a negative temperature coefficient of electrical resistance connected in parallel with said starting resistance. Preferably the resistor having a negative temperature coefficient of electrical resistance is mounted in heat receiving relation to the discharge device whereby heat generated therein causes its resistance to be reduced during the operation of the device.

In the drawing accompanying and forming part of this specification an embodiment of the invention is shown in a front elevational, partly sectional view.

Referring to the drawing the electric lamp comprises a spherical, sealed bulb 1 of vitreous material, such as glass, having a gaseous electric discharge lamp device mounted therein. The discharge device comprises a tubular container 2 consisting of a vitreous material having a high softening temperature, such as hard glass or quartz, and having therein a starting gas, such as argon or neon, or a mixture thereof, at a pressure of about 10 mm. to a few centimeters and a quantity of mercury in such an amount that it is completely vaporized during the operation of the device and produces a vapor pressure such that the operating voltage of the device is about 80% of the line voltage. A vapor pressure of about three atmospheres is desirable for this purpose.

Current leads 5 are fused into the protuberances 4 at each end of the container 2 and thermionic, activated electrodes 6 are mounted on the inner ends of said current leads 5. Preferably, each of said electrodes 6 consists of a tungsten wire helix wrapped around a pellet of material having high electron emissivity, such as barium oxide. An auxiliary electrode 7 is mounted in said container 2 adjacent each of said electrodes 6. Each of said auxiliary electrodes 7 is connected in series with a high ohmic resistance 8 to the current lead 5 of the electrode 6 opposite to that electrode 6 to which said auxiliary electrode 7 is adjacent. Said auxiliary electrodes 7 facilitate the starting of the main arc discharge between said electrodes 6 and reduces to a minimum the difference between the reignition voltage and the operating voltage of the discharge. The gaseous electric discharge device is supported in said bulb 1 by the current leads 9 and 10 fused into the press 13 of the stem of said bulb 1. Said leads 9 and 10 are connected to the leads 4 of the discharge device and the contacts on a base (not shown for purposes of simplicity) fastened to the bulb 1. When desired, an ohmic resistance 15 for controlling the starting current of the lamp is mounted in the base and a resistance 16 having a negative temperature coefficient of electrical resistance is connected in parallel with said starting resistance to short circuit the latter during the operation of the lamp. When desired these elements are mounted in the bulb 1 in heat receiving relation to the discharge device or the short-circuiting resistance alone is mounted in said bulb 1.

A resistance 11 consisting of iron wire is mounted in said bulb 1 on the support wires 12 and is concentric with the container 2 of the discharge device. Said resistance 11 is connected in series with said discharge device. The bulb 1 is filled with helium or hydrogen which gives the resistance 11 a very steeply rising positive volt-ampere characteristic.

When desired, the discharge device is enclosed by an hermetically sealed, light transmitting vitreous envelope mounted in the bulb 1 which envelope is either evacuated or is filled with oxygen and which is impervious to the helium or hydrogen in the bulb 2 in which the resistance 11 is mounted. When the container 2 consists of an ultra-violet transmitting material, such as quartz, I prefer to coat the inner surface of the bulb 1 with a visible light transmitting layer 14 of luminescent material which transforms the ultra-violet light emitted by the discharge device into

visible light to complement and supplement the light emitted by said device and to increase the efficiency of the lamp. When the lamp device is intended for use as an ultra-violet generator 5 the outer bulb 1 is made of a material which transmits these rays.

While I have shown and described and have pointed out in the annexed claims certain novel features of the invention, it will be understood 10 that various omissions, substitutions and changes in the forms and details of the device illustrated and in its use and operation may be made by those skilled in the art without departing from the broad spirit and scope of the invention.

What I claim as new and desire to secure by Letters Patent of the United States, is:

1. An electric lamp comprising in combination an hermetically sealed bulb, a gaseous electric discharge lamp mounted in said bulb and containing a quantity of vaporizable metal which is wholly vaporized during operation of the device, a resistor mounted in the space between said discharge lamp and said bulb, said resistor being an iron wire connected in series with said discharge lamp and being of such size that when operating below light-emitting temperature it dissipates less than 20% of the voltage normally consumed by said electric lamp, said bulb containing a gas from the group consisting of helium and hydrogen, a starting resistor initially connected in series with said iron wire resistor and means for automatically short-circuiting said starting resistor when said lamp is at operating equilibrium.

2. An electric lamp comprising in combination an hermetically sealed bulb, a gaseous electric discharge lamp mounted in said bulb and containing a quantity of vaporizable metal which is wholly vaporized during operation of the device, a resistance mounted in the space between said discharge lamp and said bulb, said resistance being an iron wire connected in series with said discharge lamp and being of such size that it dissipates less than 20% of the voltage normally consumed by said electric lamp, said bulb containing a gas from the group consisting of helium and hydrogen, a starting resistance connected in series with said iron wire during the starting of said electric lamp and means to short circuit said last named resistance in response to heat generated during the operation of the lamp.

3. An electric lamp comprising the combination of a sealed envelope, a charge of gas therein from the group consisting of helium and hydrogen, an electric discharge device mounted in said envelope, said device containing thermionic electrodes, a charge of rare gas and mercury of such quantity that it is wholly vaporized during operation of said device, an iron wire resistance mounted in series with said device in heat-receiving relation thereto within said envelope, said wire being proportioned to dissipate when operating at a temperature below light-emissive temperatures less than 20 per cent of the total voltage consumed by said lamp during normal operation, a starting resistance connected in series with said iron wire and another resistance having a negative temperature coefficient connected to short circuit when heated said starting resistance during normal operation of said lamp.

MARTIN REGER.
